(57) **CLAIM**

We claim the ornamental design for a cutting tool with W-shaped flute gully, as shown and described.

DESCRIPTION

FIG. 1 is an isometric top view of a cutting tool with W-shaped flute gully showing our new design with seven W-shaped flutes;

FIG. 2 is a side view thereof;

FIG. 3 is a front view thereof;

FIG. 4 is a rear view thereof; and,

FIG. 5 is a cross sectional view thereof with seven W-shaped flutes, taken along line 5-5 in FIG. 2.
